UNITED STATES PATENT OFFICE.

ANDREW D. MOYE, OF WRIGHTSVILLE, GEORGIA.

QUILTING-FRAME.

SPECIFICATION forming part of Letters Patent No. 655,567, dated August 7, 1900.

Application filed October 8, 1897. Renewed June 26, 1900. Serial No. 21,684. (No model.)

To all whom it may concern:

Be it known that I, ANDREW D. MOYE, a citizen of the United States, residing at Wrightsville, in the county of Johnson and State of Georgia, have invented certain new and useful Improvements in Quilting-Frames; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in quilting-frames; and the novelty resides in the peculiar combinations and the construction and arrangement of parts, all as more fully hereinafter described 20 and then particularly pointed out in the claim.

My invention is clearly illustrated in the accompanying drawings, which, with the letters of reference marked thereon, form a part 25 of this specification, and in which—

Figure 1 is a perspective view of my improved quilting-frame shown holding the quilt in a taut relation in readiness for the quilting operation. Fig. 2 is an end elevation 30 showing the quilting-frame folded. Fig. 3 is a cross-section taken on line 3-3 of Fig. 2, showing the relative arrangement of the parts.

Reference now being had to the details of 35 the drawings by letter, A A designate the legs of the frame, which are pivoted together by means of a bolt B at substantially the longitudinal center of the said legs, and at the upper ends of each of said legs are carried the 40 rolls C, which are supported by the screws D, which are mounted in apertures at the upper ends of the legs, said screws being securely fast to the rolls, while the shank of each screw is allowed to rotate in the aperture at the upper 45 end of the leg, and a thumb-screw D' is provided on the outer end of each screw in order to hold the roll from turning. Mounted

on the said screws are the folding braces F, which are hinged together at their inner ends, as at F', and the said braces are separated a 50 slight distance from the folding legs by means of washers E, interposed between the braces and the legs, as shown clearly in Fig. 3 of the drawings. These braces, which are arranged at opposite ends of the quilting-frame, are 55 adapted to fold down as the legs are folded together, as clearly illustrated in Fig. 2 of the drawings. Disposed along the length of the brace-sections are apertures f, which allow the braces to be held at different locations on 60 the said screws when it is desired for any purpose to bring the rolls nearer together.

From the foregoing it will be seen that a quilting-frame constructed in accordance with my invention will produce a frame which 65 is easily and quickly adjusted both in a vertical and lateral direction, holding the fabric taut by means of the folding braces, which are utilized and when folded will occupy a compact space.

Having thus described my invention, what I claim to be new, and desire to secure by Letters Patent, is—

The improved quilting-frame herein described, consisting of the pivoted legs, the 75 jointed braces extending across the ends of the frame, rolls held between the upper ends of the legs and bearing against said braces, screws with threads at each end and unthreaded shank between the threads, said 80 screws being passed through the upper ends of the legs and through the braces and rotatable in the same, with their inner threaded ends fast in the rolls, washers between the braces and legs, and thumb-nuts on the outer 85 threaded ends of said screws, all substantially as herein shown and for the purpose specified.

In testimony whereof I affix my signature in presence of two witnesses.

ANDREW D. MOYE.

Witnesses:

WM. FAIRCLOTH,
JAS. F. FLANDERS.
